United States Patent

Des. 240,908
Patented Aug. 10, 1976

240,908

WATCHFACE

Victor P. Nozdrea, 69—44 Olcott St.,
Forest Hills, N.Y. 11375

Original design application Aug. 15, 1974, Ser. No.
497,633. Divided and this application June 13,
1975, Ser. No. 587,321

Term of patent 14 years

Int. Cl. D10—07

U.S. Cl. D10—126

FIG. 1

FIG. 2

FIG. 1 is a top plan view of a watchface showing my new design, the bottom being conventional; and

FIG. 2 is an end elevational view thereof, the opposite end being a mirror image thereto.

This is a divisional of applicant's co-pending design patent application Ser. No. 497,633, filed Aug. 15, 1974, covering a wristwatch.

I claim:

The ornamental design for a watchface, as shown and described.
